UNITED STATES PATENT OFFICE.

ALBERT R. HOFFMAN, OF DECATUR, ILLINOIS.

BOTTLE OR JAR CLOSURE.

1,164,939.

Specification of Letters Patent. Patented Dec. 21, 1915.

Application filed September 29, 1914. Serial No. 864,109.

To all whom it may concern:

Be it known that I, ALBERT R. HOFFMAN, a citizen of the United States, residing at Decatur, in the county of Adams and State 5 of Illinois, have invented new and useful Improvements in Bottle or Jar Closures, of which the following is a specification.

An object of the invention is to provide 10 a closure for bottles or jars which is particularly adapted for use in connection with preserve jars and the like for preserving the contents thereof in an air-tight condition.

The invention contemplates, among other 15 features, the provision of a closure for jars which can be readily applied and as easily removed, the closure being so arranged and coöperating with suitable means whereby the usual difficulty in removing the closures from jars containing preserves and which 20 have been packed away for a great length of time, is obviated by reason of the simple arrangement which, without hurting or bruising the fingers, permits of readily removing the closure of the jar.

25 In the further disclosure of the invention reference is to be had to the accompanying drawings, constituting a part of this specification, in which similar characters of reference denote corresponding parts in all the 30 views, and in which:

Figure 1 is a fragmentary front elevation of the jar and closure, the dotted lines indicating the unlocked position of the closure mechanism; Fig. 2 is a fragmentary rear 35 elevation; Fig. 3 is a vertical sectional view taken on the line 3—3 in Fig. 1; and Fig. 4 is a horizontal sectional view taken on the line 4—4 in Fig. 1.

Referring more particularly to the views, 40 I provide a jar body 10 and a closure body 11 arranged to repose upon a seat 12 on the jar body 10, said closure body 11 having a circular depending flange 13 adapted to lie within the jar body and which aids in supporting the usual gasket or rubber ring 14 upon the closure body, the said ring being 45 adapted to bear against the seat or upper edge of the jar body. The closure body has diametrically opposed extensions 15 which 50 project beyond the periphery of the jar body and which are provided with horizontal grooves 16 extending transversely to the extension.

The jar body 10 is preferably provided 55 with an annular groove 17 in which is arranged a band 18 encircling the jar body,

said band having a stud 20 formed therewith and projecting outwardly from the periphery of the jar body. Mounted to swing upon the band 18 at the rear thereof is a 60 member 21 of substantially U-shaped construction and which is adapted to pass over one of the extensions 15 and have a transverse portion thereof pass through one of the grooves 16 in the extension. 65

Mounted to turn upon the stud 20 is a locking member 22 consisting, more particularly, of a substantially circular plate or disk 23 having an eccentric or cam 24 thereon and also provided with a suitable handle 70 25. The cam 24 has an annular groove 26 in the periphery thereof and a member 27 has its lower portion arranged to operate in the groove of the cam and its upper transverse portion adapted to pass through the 75 groove 16 of the other extension 15 so that the members 21 and 27 will effectually hold the closure body in sealed position on the jar body when the locking members are operated, as will be hereinafter more fully disclosed. 80

Now it will be apparent that when the main portion of the cam 24 lies substantially above the point of pivotal connection of the locking member with the stud, the securing member 27 will be loose relatively to the cam so that it can be disengaged from the closure body and the closure body then swung upon the member 21 and also disengaged therefrom to permit of entirely removing the closure body from the jar body. Similarly, when it is desired to apply the closure body to the jar body, one of the extensions of the closure body is first engaged with the member 21 so that a transverse portion of the member will pass through the groove of the extension. The closure body is then swung downwardly upon the jar body so that the gasket or ring 14 will bear against the seat 12 and the other member 27 is then arranged over the opposite extension of the closure body so that the transverse portion of the member 27 will pass through the groove of the other extension. 90 When this has been accomplished the handle 25 is grasped and the locking device rotated relatively to the stud 20, thus causing the cam 24 to exert a pull upon the member 27 and force the closure body into sealed 95 relation with the jar body, said cam, when 100 in its lowermost position, having its most effective locking action upon the member 27, 105 110

with the handle 25 adapted to bear against the member 27 when in its final position, thereby limiting the locking movement of the locking device. For this reason, the free end of the handle is preferably twisted so that a portion thereof will lie flat against a side of the member 27, as will be clearly seen by referring to Fig. 1.

From the foregoing description it will be clearly seen that the device described consists of few parts and that in the provision of the locking devices set forth herein the cover or closure body can be effectually secured in sealed position and will be particularly adaptable for use in connection with jars that are used in preserving and the like and wherein the contents, due to their condition, would tend to produce a pressure against the closure body which would tend to unseal the same and permit the entrance of air into the jar body if the closure body is not properly sealed and secured.

Having thus described my invention, I claim:

25 In combination with a jar body and a closure body therefor, diametrically opposed grooved extensions on the closure

body and projecting beyond the periphery of the jar body at its upper end, a band encircling the jar body, a securing member mounted to swing on the band and extending into the groove of one of the extensions, a stud projecting from the band, a disk, mounted to rotate on the stud, a grooved member on the disk and eccentric to the point of pivotal connection of the disk with the stud, a second securing member for engagement with the other extension of the closure body, said second securing member coöperating with the eccentric member, and a handle on the disk whereby, when the disk is operated, said eccentric member will be operated to exert a pull on the last mentioned securing member and move the closure body into sealed position on the jar body, with the said handle having a stop member to limit the locking action of the said eccentric member.

In testimony whereof I affix my signature in presence of two witnesses.

ALBERT R. HOFFMAN.
